ATTORNEYS.

UNITED STATES PATENT OFFICE.

FLORENCE NALLY, OF NEW YORK, N. Y.

CONTAINER.

Application filed March 12, 1924. Serial No. 698,765.

This invention relates to containers and more particularly to a container for storing scraps of nitrocellulose products and the like.

5 More specifically, this device is designed for use in motion picture studios, theatres, and other places where scraps of nitro-cellulose film and the like must be disposed of or cared for temporarily, and, due to the fact 10 that this material is highly combustible, ordinary receptacles constitute a source of danger which my container is designed to overcome. In many States this danger being recognized, legislation and proposed 15 legislation, having in view fire prevention due to this highly combustible material, has attempted to regulate its disposal in ways which are either expensive to the producer or impractical in results.

20 It is, therefore, the primary object of my invention to provide a container which will be absolutely fireproof and yet which enables the material to be readily placed therein from time to time and removed therefrom 25 upon occasion, and enables the film or other nitro-cellulose products to be kept dry at all times, thus, with safety, conserving the nitrite in same, and with a view to complying with all possible fire laws.

30 With these and other objects in view, the invention consists in certain novel features of construction and combinations and arrangements of parts which will be more fully hereinafter described and pointed out 35 in the claim.

In the accompanying drawings—

Figure 1 is a perspective view illustrating my improved container;

Figure 2 is a view in vertical section on 40 an enlarged scale;

Figure 3 is a view in transverse section on the line 3—3 of Figure 2.

The reference character A is employed to represent my improved container as a whole, 45 and the car 1 indicates the outer water receptacle, and the reference character 2 the inner receptacle for the combustible material. The outer receptacle A is supported on an axle 3 having wheels 4 at its ends. A 50 small roller or caster 5 is connected to a bracket 6, fixed to the bottom of the receptacle A, and this caster 5 and the wheels 4 provide a support for the container which will prevent upsetting but which will facilitate the movement of the container from 55 place to place. A handle 7 is secured to the receptacle A and is of any desired form and in convenient location for the operator.

It is to be noted particularly by reference to Figures 2 and 3 that the inner receptacle 60 2, while of the same general contour, shape and outline as the outer receptacle 1, is appreciably smaller in all dimensions than said outer receptacle so that a complete water jacket is provided around the inner receptacle. 65

To properly mount this inner receptacle I preferably secure feet 8 to the bottom thereof, which feet are, in turn, secured to the bottom receptacle A, and, furthermore, I 70 preferably provide outwardly bowed arms 9 secured to the receptacle 2 and engaging the inner face of receptacle 1. A watertight hinged cover 10 is provided at the top of receptacle 2 and a handle 11 is fixed to this 75 cover 10 to facilitate its movement.

The receptacle 2 is preferably provided with an asbestos or other fireproof lining 12, and a vent tube 13 connects the inner receptacle 2 with the outside air to allow gases 80 which may accumulate in the inner receptacle to escape. A hinged cover 14 is provided on the outer receptacle 1 and a handle 15 is secured to the cover 14 to facilitate movement. This cover 14 is also rendered 85 watertight in any approved manner.

On the outside of the receptacle 1 a bracket 16 is fixed and supports a bucket 17, the latter preferably having a bail 18 normally positioned over a hook 19 on the receptacle. Just above this bucket 17 and in a plane slightly below the top of receptacle 2 a faucet 20 is provided in the wall of receptacle 1. This faucet is normally closed but when it is opened it will permit the 90 water in the upper portion of receptacle 1 to drain into the bucket 17, and the level of water will fall below the upper end of receptacle 2. The covers 14 and 10 can then be opened and scrap located in the inner receptacle or removed therefrom. The cover 10 is then closed and the bucket 17, which is of a size to accommodate the water drained as above explained, can then be removed 95 from the bracket 6 and the water poured back into receptacle 1. The cover 14 is then 100 105

closed, and it will thus be noted that when the parts are in normal position the inner receptacle 2 is entirely surrounded by water, hence, absolutely preventing danger from fire.

It is this broad idea of providing a container having an inner receptacle for highly combustible material surrounded entirely by water that constitutes the broad idea of my invention, and while I have illustrated a simple and preferred embodiment of the invention it is obvious that various slight changes and alterations might be made in the general form of the parts described without departing from my invention, and hence I do not limit myself to the precise details set forth but consider myself at liberty to make such slight changes and alterations as

fairly fall within the spirit and scope of the appended claim.

20

I claim:

A device for preventing damage from combustion in moving vehicles, comprising an outer receptacle, an inner receptacle located centrally in the outer receptacle and spaced from all walls of the outer receptacle, a water-tight cover on the inner receptacle, a cover on the outer receptacle, a vent tube connected to the inner receptacle and projecting through the wall of the outer receptacle, and a faucet on the outer receptacle and adapted to drain the upper portion only of the outer receptacle and located in a horizontal plane just slightly below the top of the inner receptacle.
